UNITED STATES PATENT OFFICE.

NEAL TRIMBLE MCKEE, OF MOUNT VERNON, NEW YORK, ASSIGNOR TO THE SUPER-HEATER COMPANY, OF NEW YORK, N. Y.

FORGING MACHINE.

Application filed April 25, 1923, Serial No. 634,633, and in Great Britain May 19, 1922.

This invention relates to forging machines of the type employed for forging together a pair of pipes in the manufacture of superheater elements and the like. More particularly the invention relates to machines having pairs of gripping and forming dies between which the pipes are inserted and a reciprocating punch cooperating with the forming dies to effect the forging operation.

The object of the invention is to provide an improved machine in which the forging operation is carried out more expeditiously than hitherto whereby the life of the dies is prolonged and the lowering in temperature during the insertion of the tubes into the machine and the actual forging is reduced whereby the risk of formation of bad joints is avoided.

The invention consists in a forging machine comprising a reciprocating forging tool, and a reciprocating prime mover for operating said tool, the movement of said prime mover in one direction causing a complete reciprocation of the forging tool.

According to one convenient form the forging tool is reciprocated through the agency of toggle levers the operation of which is controlled preferably by a compressed air cylinder.

According to a further feature of the invention the gripping and forming dies are simultaneously opened or closed, preferably by means of a toggle lever operated by an air cylinder.

Further features of invention will be hereinafter described and defined in the claims.

In the accompanying drawings which illustrate a forging machine according to the invention:

Figs 1 and 2 show the ends of a pair of pipes before and after the forging operation respectively.

Fig. 3 is an outside elevation of the machine illustrating particularly the controlling valves and pipe lines for the compressed air.

Fig. 4 is a sectional elevation on the line 4, 4 of Figure 5.

Fig. 5 is a plan.

Fig. 6 is a sectional elevation on the line 6, 6 of Fig. 5.

Fig. 7 is a sectional elevation on the line 7, 7 of Fig. 5, while

Fig. 8 is a detail of the air cylinder for operating the punch.

The machine to be described is adapted for forging the ends of a pair of tubes together as illustrated in Figs. 1 and 2 according to the process claimed in Patent No. 1,169,209.

In carrying the invention into effect as illustrated in the drawings a pair of gripping dies 9, 10 is provided at one end of the machine. The die 10 is fixed in the bed 11 of the machine while the die 9 is mounted on the lever 12 pivoting on the shaft 13. The die 9 is held upon the lever 12 by the bolt 14 and in order to provide for a slight rocking of the die a space is left between the die and the surface 15 of the recess in the lever in which it is located, a pin 16 being provided between the die and the lever. A spring 17 is provided in a recess in the lever and abuts against the head of the bolt 14.

At a suitable distance from the gripping dies a pair of forming dies 18 and 19 is provided the die 18 being mounted rigidly upon a lever 20 pivoting on the shaft 13, while the die 19 is rigidly mounted on the bed 11 of the machine. The dies 18 and 19 are firmly gripped to the lever 20 and the bed of the machine respectively by the bridge pieces 21 and 22 and bolts 23 and set screws 24.

The gripping and forming dies are provided with suitable recesses to take the pipes to be forged together.

In order to pivot the levers 12 and 20 so as to close the dies a compressed air cylinder 25 is provided suitably bolted to the framework of the machine. The piston 26 of the air cylinder operates through the member 27 upon the toggle levers 28, 29 to which the upper end of the member is connected by a pin 30. The levers 28 pivot upon a shaft 31 carried in brackets 32 extending laterally of the framework of the machine. The lever 29 terminates in a spherical end 33 which seats in a correspond-

ing recess in a cross lever 34 the ends of which are located in recesses 35 in the die carrying levers 12 and 20. Pivotal connections are formed between the cross lever 34 and the levers 12 and 20 by the hinge pins 36 carried by the levers 12 and 20. The spherical seat in the cross lever 34 may be disposed midway between its ends.

The member 27 is provided at its lower end with a spherical surface 37 which seats in a cavity in the piston 26 whereby the curved path of the pin 30 is permitted. The upper end of the member 27 is forked as seen in Fig. 3 and a pin 38 is located between said forks, the pin 38 being carried by a crosshead 39 mounted upon the piston 26.

In order to permit adjustment of the toggle 28, 29 the levers 28 are mounted upon an eccentric portion of the shaft 31 and the latter is provided with a suitable squared end whereby it may be partially rotated to make the necessary adjustment. A wheel or disc 40 having a serrated or toothed periphery and rigidly mounted upon the shaft 31 provides a suitable device for holding the shaft in its adjusted position, a screw 41 carried by the framework being provided for engagement with said teeth or serrations.

When the dies are in closed position as indicated in Figs. 6 and 7 the forming dies are positively held together by means of the locking lever 42 which is pivoted in a bearing 43 carried by the lateral brackets 32 of the framework. The locking lever 42 automatically moves into the locking position, on closing the dies, by the action of the spring 44. One end of the latter is connected to a pin 46 carried by the framework while the other end is connected to the foot lever 47 pivoted at 48 and having a pedal 49. A link 50 connects the foot lever with the locking lever 42.

After the forging operation the locking lever is removed from the locking position by pressure on the pedal 49. The die carrying levers 12 and 20 project through recesses 51 in the bed of the machine and are guided by the central packing piece 52, the plate 53 and the guiding members 104. The plate 53 and guiding member are rigidly held in position by bolting to the framework while the packing piece is loosely held in position by a bolt 54 and spring 55 (see Fig. 6). The packing piece 52 and plate 53 are suitably cut away to permit the insertion of the work piece, the framework of the machine being suitably recessed at 56.

In axial alignment with the dies is the forging punch 57 which has a portion 58 adapted to slit the tubes and a forging shoulder 59.

The punch 57 is carried in an adjustable holder 60 which in turn is carried by the

plunger 61. The latter is adapted to reciprocate in the cylindrical seating 62, rotation being prevented by the flat surface 63 on the plunger contacting with a wearing strip held in position by the cover plate 64.

The adjustable holder 60 is dovetailed into the plunger and is gripped in position by the bolt 65 passing through both members, the hole on the part 60 being larger than the bolt whereby lateral adjustment of the holder with reference to the plunger may be effected.

The punch is held in the holder in a similar manner by the bolt 66 whereby vertical adjustment of the punch with reference to the holder may be effected.

Reciprocation of the plunger 61 is effected by means of the toggle levers 67, 68 one of which 67 is connected at 69 to the plunger while the other is connected at 70 to a fulcrum bracket 71 fixed by bolts 72 to the rear end of the machine.

Referring to Fig. 3 actuation of the toggle 67, 68 is effected by the double acting compressed air cylinder 73 the piston rod 74 of which is connected by the link 75 to the pivot of the toggle.

The cylinder 73 is fixed to the casing 76 by studs 77 and the casing is pivoted on the brackets 78 by means of the trunnions 79.

The toggle 67, 68 is adapted to be moved from the position indicated in Fig. 3 across the dead centre and to the position indicated in Fig. 4 thus causing the punch to operate and be withdrawn by a single stroke of the piston.

In order to adjust the longitudinal travel of the punch 57 the position of the fulcrum bracket 71 is adapted to be adjusted with reference to the framework of the machine. For this purpose a packing piece 80 is provided between the bracket 71 and projecting part 81 of the machine.

The controlling gear will now be described with reference to Fig. 3. Compressed air is supplied by the pipe 81 and is led by the pipe line 82 to the valves 83 and 84 controlling the air cylinder 73. Pipe line 85 connects the valves 83 and 84 to the cylinder 73. The valves 83 and 84 are actuated by hand by the hand lever 86 and links 87, 88. The valve 83 is a comparatively small valve and air will flow through it at a slow rate so as to cause a gentle closing of the dies before full pressure is admitted to the cylinder by the valve 84.

Branch pipes 89, 90 connect up the inlet valves 91, 92 to the pipe line 82. Actuation of the valves 91, 92 by means of the foot lever 93 and link 94 admits air through pipe lines 95 to the cylinder 73 to effect the forging and withdrawal of the punch 57. The return stroke of the cylinder 73 is caused by the operation of the valve 96 which connects the cylinder with pipe line 130

82 by way of branch 97 and pipe 98. The valve 96 is controlled by the hand lever 99 and link 100.

The operation of the machine is as follows:

After insertion of the pipes between the dies, the valves 83 and 84 are opened, seriatim, by the lever 86 to effect the simultaneous closing of the gripping and forming dies

10 9, 10, and 18, 19.

The locking lever 42 automatically locks the forming dies 18, 19 under the action of the spring 44. Air is then admitted to the cylinder 73 by actuating the foot lever 93 15 against the action of the spring 101 to open the valves 91, 92. Such action causes the punch 57 to move into and out of the work.

Releasing the foot lever 93 allows the spring 101 to return the valves 91, 92 into 20 the exhaust position. The locking lever 42 is then withdrawn by pressing on the foot pedal 49. Movement of the lever 86 to the exhaust position allows air to exhaust from cylinder 25 and releases the gripping and 25 forming dies 9, 10 and 18, 19 the levers falling back under their own weight. The foot pedal 49 is then released so that the locking lever 42 rests upon the upper end of the lever 20.

30 By means of the valve 96 operated by the lever 99 air is admitted to cylinder 73 to return the toggle 67, 68 to the "up" position after which the lever 99 is again moved to put valve 96 in exhaust position. The cycle 35 may now be repeated.

In order to provide a cushioning effect at 40 the end of the operative or down stroke of the cylinder 73 a rubber washer 102 (Fig. 8) is provided and in addition the exhaust of the valve 96 is throttled to a suitable 45 degree.

A gauge plate 103 is provided at the end 50 of the machine to limit the length of pipe inserted into the machine.

It will be obvious that by a suitable modified arrangement of valves controlling the air cylinder 73 the return stroke of the piston may be utilized to effect a forging operation.

55 It is to be noted that the framework of the machine adjacent the end in which the tubes are inserted is cut away or so formed that the width thereof is reduced as much as possible in order to facilitate the handling of superheater units comprising a plu-

rality of return bends so that the parts not being operated upon are not liable to become damaged. For the same purpose the dies are arranged at the extreme upper part of the machine.

60

By means of a machine operating according to the above described principles the lapse of time between the insertion and gripping of the tubes in the dies and the operation of the punch may be reduced to a minimum whereby the reduction in temperature of the work is much lower than with machines hitherto employed, and further the insertion and withdrawal of the forging tool is more expeditious than hitherto, thus 70 prolonging the life of the tool. By this speeding up of the process the risk of imperfect joints is practically eliminated.

It will be obvious that many modifications may be made without departing from the 75 scope of the invention.

What I claim is:

1. In a forging machine, the combination of a pair of gripping dies, a pair of forging dies alined with them, one die of each pair being mounted to a fixed portion of the machine, the other dies being mounted each to a lever, and mechanism to move the two levers simultaneously about their pivots so as to open or close the two dies simultaneously.

2. In a forging machine, the combination of a pair of gripping dies, a pair of forging dies alined with them, one die of each pair being mounted to a fixed portion of the machine, the other dies being mounted each to a lever, a cross-lever engaging both levers, a toggle joint one movable end of which engages the cross-lever, and mechanism to operate the toggle joint.

3. In a forging machine, the combination of a pair of gripping dies, a pair of forging dies alined with them, one die of each pair being mounted to a fixed portion of the machine, the other dies being mounted each to a lever, a cross-lever engaging both levers, a toggle joint the movable end of which engages the cross lever at its mid-point by means of a spherical joint, a cylinder, a piston reciprocable in the cylinder, means operatively connecting the piston to the middle joint of the toggle, and means to admit pressure fluid to the cylinder.
